TUMBLER LOCK ADJUSTABLE FOR
DIFFERENT KEYS

Stephen Pelle, Bronx, N. Y.

Application March 19, 1949, Serial No. 82,455

2 Claims. (Cl. 70—382)

1

This invention relates to locking devices.

It is an object of the present invention to provide a locking device which can be easily altered to match different keys so that upon the normal user of the lock giving up its use, the lock can be changed to prohibit his future use by the new occupant of the space placed under the lock and key and also a lock which is particularly adapted for use in hotels whereby, with a simple adjustment, the lock can be changed even after each use of the key by the occupant.

Other objects of the present invention are to provide an adjustable locking device which is of simple construction, inexpensive to manufacture, easy to adjust, has a minimum number of parts, compact and durable, easy to install in the door, and efficient in operation.

For other objects and for a better understanding of the invention, reference may be had to the following detailed description taken in connection with the accompanying drawing, in which

Fig. 1 is a perspective view of the adjustable locking device embodying the features of the present invention.

Fig. 2 is a fragmentary and sectional view, in part, of the locking device assembled upon a door.

Fig. 3 is a longitudinal sectional view taken on line 3—3 of Fig. 1.

Fig. 4 is a longitudinal sectional view taken on line 4—4 of Fig. 1, at a different angular position.

Figs. 5 and 6 are respectively transverse sectional views taken respectively on lines 5—5 and 6—6 of Fig. 3.

Fig. 7 is a perspective view of the key operated elements.

Fig. 8 is a perspective view of the adjustable key receiving element.

Fig. 9 is a side elevational view of the adjustable element shown in Fig. 8.

Fig. 10 is a transverse sectional view taken on line 10—10 of Fig. 9.

Fig. 11 is a longitudinal sectional view of the fixed key receiving elements taken on line 11—11 of Fig. 7.

Fig. 12 is a perspective view of the key engaging member which is adjustable within the elements.

Fig. 13 is a collective and perspective view of the key receiving element casing parts.

Figs. 14 and 15 are respectively front and rear face views of the key opening.

Fig. 16 is a fragmentary longitudinal sectional view taken through locking element for the adjusting gear.

2

Referring now to the figures, 21 represents a hollow cylinder which has, at one end thereof, external threads 22 for securing the cylinder within a hole 23 of a door 24. Integral with the opposite end of the cylinder is a plate or flanged formation 25 which will appear at the front of the door. This formation may have a plated layer 26 thereover, Figs. 3 and 4. A hole 27 extends through the plate formation and this hole is of less diameter than the interior diameter of the main part of the hollow cylinder 21. Accordingly, a shoulder 28 is provided. The cylinder 21 has longitudinally extending slots 30 and 31 into which slides 32 of slide assemblies 33 may be extended as the same are assembled within the hollow opening of the cylinder. Several slide assemblies 33 are fixed by means of a screw 34, Fig. 11, upon a plate 35 and upon rods 36 and 37 thereof. This plate 35 has a key opening 38 therein adapted to be aligned with key openings 39 of the assemblies. The plate is shouldered at 40 and this shouldered part extends into the opening 27 of the plate portion 25 on the front of the door. A key 41 penetrates these key openings 38 and 39.

Each slide assembly 33 has separable casing parts 42 and 43 which, when coupled together, retain slides 32 and a spring 44 which urges the slides outwardly. The slide has a projection 45 against which the spring 44 acts and also a projection 46 on the opposite side of the slide adapted for engagement by the key 41 as it is extended through the slide assembly. The slide assemblies may be secured together by rivets 47. Openings 48 and 49 are provided in the slide assemblies so that they can be adjusted along the rods 36 and 37. The entire assembly, as shown in Fig. 7, is placed into the cylinder so that the plate shouldered portion 40 extends through the opening 27.

A fourth slide assembly is mounted on the rods 36 and 37 and within the hollow cylinder for adjustment therealong whereby the arrangement can be adapted for different types of keys depending upon the position to which the assembly, as may be identified at 33', is located on the rods.

At other locations, there are disposed longitudinal recesses 51, 52 and 53 in the cylinder wall. These recesses are 120° apart and are adapted to slidably receive adjusting members 54 respectively which have projections 55 for receiving the adjustable slide assembly 33'. These adjusting members 54 are operated by screws 56 which project at their inner ends, as indicated at 57, into the ends of the recesses and which are journaled, as indicated at 58, in a rear plate 59. This rear plate 59 is fixed by screws 61 and 62 to the

rear end of the hollow cylinder 21. Each screw 56 has a pinion gear 63 thereon. Journalled on a sleeve projection 64 of the plate 59 is a large adjusting gear 65 meshing with each of the pinions and which, when turned, will cause the turning of the screws 56 and the adjustment of the slide assembly 33' through the adjusting members 54. A spring ring 66 secures the gear 65 upon the plate 59.

On the plate 59 is a thin plate 67 which has an axially extending member 68 fixed to the same and this member 68 extends through the plate 59 for engagement with a knob 69 on a lock casing 71. When the slides 32 of the assemblies 33 are properly depressed so that the assemblies are released from the hollow cylinder, the key will turn all of the slide assemblies and the rods 36 and 37 and the plate 67 and knob 69. The member 68 is fixed by a pin 72 to a member 73 which in turn is fixed to the plate 67.

The gear 65 has diametrically spaced holes 75 and 76 into which a pin 77 may be extended for a given adjustment of the gear 65, Fig. 16. This pin is normally held outwardly by a spring 78 lying in an opening 79 in the hollow cylinder member. Accordingly a new location of the slide assembly 33' is made for each half turn of the gear 65.

The lock casing 71 is secured to the door by screws 81. A plate 82 is fixed to the inner side of the door by screws 83. A key 84 registers with a notch in the plate 82 and in the cylinder, as indicated at 85, to keep the cylinder 21 from turning relative to its opening in the door 24.

Any shape key opening can be used, as indicated at 87 and 88, in Figs. 14 and 15. By depressing the member 77, it releases the gear 65 so as to permit the adjustment of the gear. With each adjustment of the slide assembly 33', a different formation 89, Fig. 4, will be provided upon the key 41. This projection 89 will be at different distances from the end of the key depending upon the adjustment of the assembly 33'.

While various changes may be made upon the detail construction, it shall be understood that such changes shall be within the spirit and scope of the present invention as defined by the appended claims.

What is claimed is:

1. A lock device comprising a hollow cylinder, a plurality of slide assemblies disposed within the hollow cylinder and one of said assemblies being adjustable longitudinally of the cylinder, said cylinder having a slot, each of said slide assemblies having a slide adapted to be projected into the slot and retracted therefrom, said slide assemblies being adapted to receive a key, means carried by the cylinder and connected to the adjustable slide assembly for effecting the adjustment of the slide assembly relative to the other assemblies to render the lock adaptable for a different key, an end plate connected to the hollow cylinder, means rotatable in said end plate and connectable with the slide assemblies to be adjusted by the same, said means for adjusting the adjustable slide assembly comprising a plurality of adjustable members circumferentially spaced from one another, said hollow cylinder having longitudinally extending openings, said adjustable members slidable in said openings and engageable with the adjustable slide assembly, a plurality of screws connected respectively with the adjustable members to move the same, a large gear on the end plate and journalled thereabout, pinion gears meshing with the large gear and respectively connected to the screws to simultaneously operate the same and to effect the adjustment of the adjustable slide assembly.

2. A lock device as defined in claim 1, and said large gear having circumferentially spaced openings therein, a detent device engageable with said circumferentially spaced openings in sequence to hold the gear in its adjusted position and the slide assembly at the new adjusted position.
